UNITED STATES PATENT OFFICE

2,504,751

TURRET PRESS

Hans Studli, Winterthur-Hard, Switzerland

Application August 17, 1945, Serial No. 611,077
In Switzerland June 26, 1944Section 1, Public Law 690, August 8, 1946
Patent expires June 26, 1964

10 Claims. (Cl. 18—20)

1

My present invention relates to improvements in fluid-operated presses particularly for the manufacture of bodies from synthetic resins or plastics, having a plurality of press-units each provided with a press-cylinder and press-tools or dies and secured to a turn-table structure, the latter being intermittently rotated step by step past a pay-out station for the blanks, a press-fluid tanking station, a press-fluid discharging station, and a delivery station for the final products.

The objects of my improvements are first, to render the press-units independent of any outside pressure-fluid feed by providing a single tanking station to which each press-cylinder in succession is connected at the very moment when a pressing is to take place, such a provision also saving pump power; second, to afford a positive black-feed and pay-out operation; third, to adapt the delivery mechanism for the final products also for stripping threaded products from the dies; and fourth, to control and time all individual movements and operations from a common cam shaft.

I attain these and related objects by the multiple press shown, by way of an example, in a single embodiment of an oil-pressure operated press, in the accompanying drawings, in which:

Fig. 1 is a sectional elevation of the press with one press-unit in the position of delivery of the final product,

Fig. 2 shows partly an elevation and partly a section on the line II—II of Fig. 1,

Fig. 3 a vertical section, in a larger scale, of a press device in the position of delivery of the final product, and of the device for removing the latter,

Fig. 4 a vertical section, in a larger scale, of a press device in the pressing position,

Fig. 5 a horizontal section on line V—V through the press devices, and on line V'—V', of Fig. 1,

Fig. 6 a top plan view of the blank pay-out device,

Fig. 7 a horizontal section, on line VII—VII of Fig. 9, through the drive mechanism of the latter device,

Fig. 8 an elevation of the latter,

Fig. 9 a vertical section of the latter,

Fig. 10 a part elevation of the drive for the intermittent and step-by-step rotation of the press-unit turn-table,

Fig. 11 a vertical section, in larger scale, on line XI—XI of Fig. 2, of the drive,

Fig. 12 shows, in a larger scale, a vertical section of the press tools, and

Fig. 13 a horizontal section on line XIII—XIII

2

of Fig. 1, and a top plan view of the device for removing the press products.

A turn-table in the form of a pedestal body comprising a bottom abutment 4, and a composite top abutment 6—7 connected to the latter by means of the columns 5, is pivoted, by means of roller bearings 3, on the quill 2 fastly secured to the machine frame 1. The said top abutment is built up of two flanges 6 and 7 enclosing an annular recess 8. Ten presses, spaced circularly, are secured to the bottom abutment 4 by their bored axles 29. Each of said presses comprises a hollow piston 9 (Fig. 4), upon which the press cylinder 10 may be displaced. A cylindrical holder 12 is secured to the latter by means of the shoudered stud 11. The matrix or die 13 is exchangeably secured to the said holder 12. A helical spring 14, interposed between the flange 6 and the cylinder head, tends to push the cylinder 10 downward over the piston 9 for the purpose of discharging the press-fluid which, in this case, is oil. The latter is supplied by a pump 16 continuously driven by the electric motor 15 (Fig. 1). The pressure line 18 (Fig. 4) and a pipe 19 leading to the pump suction-chamber are disposed in a casing 17, and a valve 20, intermediary of said lines 18—19, is intermittently opened and closed by a cam disc 21 by way of the lever 22 and the rod 23. In Fig. 4 the valve 20 is closed, and the press oil flows through the pipe 24 into the bored pedestal 25, the upper portion of which is acting as a cylinder 26. A hollow piston 27 reciprocates in the latter, and is provided with a valve seat 28 sealing against the valve seat 30 disposed in an extension 29 of the said piston, and providing, in accordance with its position in Fig. 4, a connection between the press-oil line 24 and the press cylinder 10. A valve 32, loaded by the spring 31, is provided in the piston 27, and a helical spring 33, bearing in the pedestal 25 and on the top of the piston 27, tends to draw the latter downwardly. The springs 33 and 31 are so designed that, when press oil enters the pedestal 25, the piston 27 is raised against the spring 33, until the seats 28 and 30 are sealed, upon which the valve 32 is opened and admits oil into the press cylinder 10.

A check valve 35 is housed in the stationary piston 9, loaded by the spring 36 and guided in the bore of the extension 29 by the stem 34. The air volume in the bore of the piston extension 29 is used for the production and, respectively, the maintenance of an air pad in the press cylinder 10. When the check valve 35 is closed, the foot portion of its guide stem 34 projects downwardly

beyond the valve seat 30, and the valve may be lifted, for the purpose of discharging the oil from the cylinder 10, by a stationary trip in the form of a roller 37 whenever the corresponding press-unit is moved thereabove in turning the turn-table 4-7.

In contrast to other presses, the press according to the present invention does not possess a stationary pressure pipe for each of the ten press-cylinders, but only this charging nozzle common to all of the latter. All pressing devices are successively charged with pressing oil by turning the turn-table 4 step by step above this dispensing nozzle.

To produce this stepwise turning movement, ten ratchet-wheel elements 38 (Fig. 10), each having a notch 39, are fastly secured to the bottom of the abutment 4 and co-act with a pawl 41 loaded by the spring 40. The said pawl is pivoted to the arm 42 of a socket 43 which is rotatable on the quill 2, and is rocked by means of a rod 44 and the cams 45 and 46 (Fig. 5). In order to stop the turn-table 4-7 in the appointed position after each switching step, an axially displaceable tapered dog 47 (Fig. 3) is provided, which engages the interdental gap 48 in the plates 49 fastly secured tangentially to the abutment 4. The dog 47 (Fig. 3) is controlled in its reciprocating movement by a cam 50 by way of the rigging 50a, 50b and 50c.

A blank pay-out device (Figs. 6-9) common to all pressing devices, is provided for feeding the material to be pressed as flat circular blanks. The said charging device comprises a disk 52 crenellated to form pockets 51 (Fig. 6) and secured on a pin 54 which is pivoted in a casing adapted as container 53. The latter is in a slanting position, i. e. inclined towards a channel 55 so that the blanks drop from the pockets 51 into the latter. The channel 55 is sloped downward toward the pressing devices to permit the blanks of sliding off into the pressing tools 13 secured in the holder 12 (Fig. 1).

The disk 52 is moved by a switch gear (Fig. 7) comprising a ratchet wheel 56 and a pawl 57 which is coupled to a dog 58 by means of a spring 59. The pawl 57 is fulcrumed in a swing arm 60 pivoted on the said pin 54 and actuated by way of a link 61 by means of a lever 62, which latter is operated by the cam disk 63. Due to the obliquity of the blank pay-out structure, the said link is provided with ball-and-socket joints. The speed at which the disk 52 is driven by the gear 56-57 is at least twice as great as required by the number of blanks fed to the tools, so as to avoid any interruption of the feed notwithstanding the possibility that some of the pockets 51 be empty. In order, now, to prevent a clogging of the trough 55 by blanks at this, for a normal feed excessive speed, a cranked feeler arm 64 is provided which projects into the channel 55 with its slotted end, on which latter a pin 65 is screw-fastened. The said arm is secured to an axle pin 66 journaled in the housing 53 and provided with a lug 67 cooperating with the pawl 57. Another lug 68 is secured to the swing arm 60, and abuts against the lug 67 when the said arm is rocked in the one direction and thus swings the feeler arm 64 into its operative position. When the swing arm 60 swings back in the other direction, the lugs 67 and 68 become separated, and the feeler arm 64 is lowered for feeling into the channel 55. When meeting a blank, this is the signal that a sufficient number of blanks are in the channel, and the lug 67 occupies such a posi-

tion that during this swinging back the rearward arm of the pawl 57 hits the lug 67, thereby turning the pawl out of the range of the ratchet wheel 56 so that no clicking takes place upon the forward swing of the arm 60. If the feeler arm 64 does not rest upon a blank, the lug 67 is in such a position as not to engage the pawl 57, the latter remaining in mesh with the switching teeth of the ratchet wheel 56 so that the disk 52 is further rotated and the trough is further charged with blanks.

To ensure that, at any one time, only one blank is moving from the trough 55 to the press tools in their charging position, a swing lever 69 is provided which on its forward end carries two knives 70 and 71 opposite one another. In the position occupied by the swing lever 69 according to Fig. 6, the knife 70 has entered into the trough 55 and is in front of the frontmost blank. If blanks have to be fed, the blade 70 is withdrawn from the channel and releases the frontmost blank to slide off toward the press tools. At the same time, the blade 71 enters into the trough and prevents the penultimate blank from sliding off together with the frontmost blank. In the succeeding play of the swing lever 69, the blade 71 releases the now frontmost blank, and all blanks in the trough slide downward, the frontmost blank being retained by the knife 70 which in the meantime has entered into the trough, and the dispensing cycle starting anew. The swing lever 69 is driven by a cam disk 72 (Fig. 2).

A device, common to all press units, for removing the final products is provided at the pay-out station. It is assumed here that we are dealing with pressed products in the form of internally threaded closure-caps for bottle and like containers. Fig. 12 shows such a cap 73 in section and the press tools. The latter comprise the bottom tool 13 which is exchangeably secured in the holder 12 and defines the outer form of the screw cap 73, and the top tool 75 provided with a threaded stud pin 74, which is exchangeably secured in the top flange 7 of the turn-table by means of the screw 76.

To remove this press product, it must be unscrewed from the top pressing tool 74-75. This is done by a sleeve 78 pivoted in a rest 77 and provided with grippers 79 which engage the pressed article 73 from outside. The sleeve 78 in its top portion is mounted by a thimble 80 which is carried by a fork 81. By displacing the latter upward, the grippers 79, which are mounted on the bell-crank 82, contact the part to be pressed.

The rest 77, which carries the sleeve 78, is rockably mounted by means of a hub 83 (Fig. 1) to permit of swinging the contrivance into the operative position shown in Fig. 13 and, after removing the pressed part, of swinging same back into the inoperative position shown in Fig. 13 by the dash-and-dot lines. The hub 83 is adjustable in elevation in order to bring the rocked sleeve 78 upward into that position in which the grippers 79 co-act with the pressed article. The rest 77 is swung in and out by the action of a cam disc 84 over a swing lever 85 and a rod 86 (Figs. 1-3). The rest 77 is raised and lowered by the action of a cam disk 87 over swing lever 88 and grooved set collar 89 screwed fast on the hub 83, while the fork 81 is raised and lowered by the cam disc 90 acting upon the swing lever 91, the grooved set collar 92 and the tappet 93. The cam discs and lever transmissions are suitably chosen so that the lowering movement is adapted to the thread pitch of the final product.

5

The sleeve 78 is rotated by a motor 94 over a V-belt drive 95-97 and gear wheels 98-102, the stationary pinion 98 having such a width of teeth as to ensure the meshing with the wheel 99 even during the vertical movements of the rest 77.

The closure cap, unscrewed from the stud 74 of the press tool 75, is still held by the grippers 79 until the take-off device has first been lowered and then swung out into its inoperative position. By depressing the fork 81 or, respectively, by lifting the rear end thereof, the grippers 79 are slackened; the final article is freed from the grippers and drops into the chute 73'.

As described above, all motions required for the stepwise turning of the turn-table with the individual presses, for the actuation of the blank-feeding device, for the feeding of a pressure-medium to each individual press, and of the device for removing the final products, and appurtenant motions are actuated by cams secured to a common cam shaft 103. The drive for the latter, as shown in Fig. 11, comprises the motor 94, a change-speed drive of the expansion roller type having adjustable cone discs 104, 105 and V-belts 106. This change-speed drive is adjusted by means of a handwheel 107 (Fig. 2), a shaft 108, bevel gears 109, spur gears 110, 111 and an externally threaded sleeve 112, which latter serves for adjusting the bottom cone disc 104 relative to the top disc 105. A worm 114 is fastly secured to the shaft 113 of the cone discs 104 and engages a worm wheel 115 secured to the cam shaft 103.

An excess pressure valve is provided in the pressure line 18 of the pump, comprising a tapered valve stem 116 and a valve seat 118 loaded by the spring 117. A handwheel 119 permits of adjusting the spring pressure and thus the desired oil pressure for the pressing operation. Cooling-water pipes 121 are disposed in the oil sump 120 (Fig. 1), which latter is formed in the bottom portion of the machine frame 1. The oil flowing out of the pressure cylinders 10 when lifting the stems 35 of the check valves, drops directly into the oil sump. Leakage oil from between piston 9 and cylinder 10 or from the check valve is caught in the pan 122 provided on the bottom abutment 4, and flows through filters 123 into the sump 120. Oil-losses due to leaks do not impair the function of the individual presses, since, as described above, an air pad is provided in each cylinder 10 which permits of only a gradual pressure drop. In the manufacture of pressed products of, e. g., a synthetic resin, it is sufficient when the maximum pressure is maintained over only a short length of time. The pressure then may gradually drop to zero during the rotation of the press devices from the oil-charging station to the pay-out station of the final product, since no special pressure is required for the condensation of the press product made of a synthetic resin.

The flanges 6 and 7 of the head structure of the turn-table are electrically heated by means of built-in resistances 124 and 125, and the press tools 75, 76 secured to the flange 7, as well as the lower tool 13 secured on the holder 12 are thus heated by convection and radiation. Thermostats 126 control the temperature of the said flange 7, and additional thermostats are provided in the flange 6. Current is supplied to the heating resistances 124 and 125 by the lines 127 which pass from below through the quill 2, and by the slip rings 128. For the purpose of heat insulation, insulating layers 129 are provided, as well as a

6

bell 130 extending downwardly over the top structure of the bearing. Said bell is suspended from wires 131 which run over sheaves 132 and are anchored in counterweights 133 to permit of readily lifting same e. g. for the purpose of exchanging the press tools.

Having described the action and operation of the various parts of the machine, a repeated description of the overall operation may be dispensed with. It will be observed that the step-by-step motion of the turn-table and thus of the ten individual presses represented in Fig. 13, is taking place, e. g., in the sense of the arrow shown. One of the said presses being positioned at the delivery station A for the final products, the preceding press is under the pay-out station B for the blanks, the second preceding under the charging station C for the pressure-medium, while the next following is on the point D, on which the pressure-medium is discharged by lifting the check valve and where the pressure tools are moving away from each other. In the presses positioned between the points C and D the condensation of the synthetic resin is taking place, if such a material is used for the manufacture of the pressed articles. All of the ten pressing devices pass these points one by one.

In such an individual press more than a pair of pressing tools may be disposed also, and instead of removing the final products by means of the grippers described, they also may be blown off the upper or the lower press tools, provided that they are not threaded. The compressed-air feed may be controlled by a cam 134 of the cam shaft 103.

Only those features of the machine which are of specific interest for its operation, have been described above. Aside from these, safety devices are provided for, such as electrically operated locking appliances which, e. g., permit of moving the turn-table only when, e. g., the cylinder has reached its lowest position, in order to prevent a collision between the device for removing the pressed products and the lower pressing tools which have not yet been entirely lowered, which might cause damages to the machine.

What I claim and desire to secure by Letters Patent is:

1. A press of the class described, comprising in combination, a turn-table, a plurality of press-units each provided with a pressure cylinder reciprocably mounted on said turn-table and with a die fixedly secured to said turn-table, means for intermittently turning said turn-table to bring each press-unit successively into a determined position in which each press-unit starts its operation, a blank pay-out mechanism for dispensing blanks to each press-unit successively, a pump supplying pressure fluid, a pressure dispensing device, coupling means included in said pressure dispensing device and arranged at said operating position for mechanically connecting successively each pressure cylinder with said pressure dispensing device for producing the pressed article, a pressure relief valve in said pressure dispensing device and arranged on the pressure side of said pump, a final-product delivery mechanism including means for removing the pressed articles from the dies of each successive press-unit, and cam means for controlling said pressure relief valve and the means for intermittently turning the said turn-table and the said blank pay-out and final-product delivery mechanism in timed relationship.

2. A press according to claim 1, and in which

the pressure dispensing device comprises a stationary cylinder, a conduit for supplying pressure fluid to said cylinder, a spring-loaded hollow piston reciprocable in said cylinder and forming part of said coupling means for mechanically connecting the press cylinders of successive superjacent press-units by action of the fluid pressure, and a spring-loaded valve disposed within the said hollow piston and opening only when the said connection has been established.

3. A press according to claim 1, and a hollow piston provided in the cylinders of each press-unit and secured to and extending downwardly through the said turntable and having a central bore, a spring-loaded check valve disposed within the said piston, and a valve stem guide extending through the said bore to project from the lower end thereof and of a length which is a multiple of its diameter, the air volume in said guide providing and maintaining an air pad in the said cylinders of the press-units at each pressing operation, and a stationary dog disposed below the turntable for cooperation with the said check-valve stem lifting the latter when a press-unit passes over it for the purpose of discharging the press-fluid from the said cylinder.

4. A press as claimed in claim 1, and in which the said blank-pay-out mechanism comprises a magazine disc supporting blanks and inclined toward the press-units, a similarly inclined chute for receiving the blanks from said magazine disc, driving means for rotating said magazine disc intermittently, and safety means for interrupting said driving means when said chute is filled with blanks.

5. A press as claimed in claim 1, and in which the blank-pay-out mechanism comprises a magazine disc supporting blanks, an inclined chute for receiving the blanks from the latter, and a magazine-disc drive comprising a pawl-and-ratchet device, a swing lever operating the latter and actuated from the cam shaft, and a feeler lever projecting into the said chute and adapted to disengage the pawl from the ratchet wheel when contacting a blank in the said chute.

6. A press according to claim 1, and a blank-feed mechanism having a magazine disc for supporting blanks, an inclined chute for receiving the blanks from the latter and feeding same one by one into passing press-units, and comprising a swing lever having two blades opposite each other

and projecting into the said chute, one of said blades releasing the front-most blank in the said chute upon an outward movement of the said swing lever while the other blade at the same time passes in front of the succeeding blank and prevents same from sliding off into the respective press-unit.

7. A press as claimed in claim 1, and in which the said blank-pay-out mechanism comprises a magazine disc supporting blanks and inclined toward the press-units, a similarly inclined chute for receiving the blanks from said magazine disc, driving means for rotating said magazine disc intermittently, and at least twice as fast as required by the number of blanks necessary for feeding the press-units so to eliminate any interruption in the blank-feed due to the magazine disc being not fully charged.

8. A press according to claim 1, and a final-product delivery mechanism comprising a device for removing the final products from each press-unit in succession, and controlled from the said cam shaft, said device being rockable horizontally and displaceable vertically.

9. A press according to claim 1, and a final-product delivery mechanism having a device for stripping the threaded final product from each press unit in succession and controlled from the said cam shaft, said device being rockable horizontally and displaceable vertically, and comprising a gripper rotatably engaging the final product in the manner of a wrench for the purpose of unscrewing the product from the die, the said vertical displacement being adapted to the steepness of the thread pitch on the final product.

10. A press according to claim 1, and in which the drive mechanism for the said cam shaft includes a change-speed gear.

HANS STUDLI.
